(No Model.)

F. A. GOODRIDGE.
THREAD CABINET.

No. 498,784.

Patented June 6, 1893.

UNITED STATES PATENT OFFICE.

FREDERICK A. GOODRIDGE, OF ST. LOUIS, MISSOURI.

THREAD-CABINET.

SPECIFICATION forming part of Letters Patent No. 498,784, dated June 6, 1893.

Application filed August 20, 1892. Serial No. 443,651. (No model.)

To all whom it may concern:

Be it known that I, FREDERICK A. GOODRIDGE, a citizen of the United States, residing in the city of St. Louis, State of Missouri, ⁵ have invented certain new and useful Improvements in Thread-Cabinets, of which the following is a full, clear, and exact description.

My invention relates to cabinets for containing the broken stock of thread from which the same is sold in the retail trade, and has for its object a cabinet that in itself and in the manner of using the same shall occupy a minimum of store-space, one in which provision is made to keep the thread of different colors—¹⁰ black and white—separate, to keep the different sorts, or number, of the same color separate, one in which, when it is desired to get at some particular number of a required color, all the sorts of that color are brought to plain ¹⁵ view, and are conveniently gotten at without disturbing other sorts or mixing the colors.

It consists in the novel features in the construction of thread-cabinets hereinafter described, in the details of improvement by ²⁰ which the desirable results, enumerated above, are effected, and in the details of improvement embodied in the cabinet drawer hereinafter described.

In the accompanying drawings, in which ²⁵ like letters of reference denote like parts in the several views, Figure 1 is a side elevation of my improved cabinet. Fig. 2 is a front elevation of the same, showing one of the hinged sections, hereinafter described, opened. Fig. 3 is a horizontal section, taken on the line 3—3 in Fig. 1. Fig. 4 is a horizontal section, taken on the line 4—4 in Fig. 2. Fig. 5 is a vertical section, taken, through ³⁵ part of the height of the cabinet, as on the line 5—5 in Fig. 3; and Fig. 6 is a vertical section, taken on the line 6—6 in Fig. 5.

I have illustrated a simple, square, upright, cabinet, with one drawer, in which are set forth the features of my invention.

The body proper of my improved cabinet is ⁴⁰ divided by the partition piece A, which extends from front to back and top to bottom of the cabinet, except the lower part, which is occupied with drawers, into the two distinctly ⁴⁵ separate right and left parts W and B. Each of these parts W and B is again similarly

subdivided into the substantially equal front and rear parts F and R and F' and R', respectively, see Fig. 4. The parts R and R', in each instance, are built in the cabinet, being inclosed on three sides by the inclosing side panels C, which are secured to the base-board D and the top-board E, and the partition-piece A. Each of the sections R and R', as well as the sections F and F', are provided ⁵⁵ with a number of shelves a dividing the sections into a number of compartments vertically disposed. These compartments are again subdivided, by the partition-ribs b, into any number of individual compartments—⁶⁰ two, as shown—as may be found convenient. The two sections F and F' are each hinged, by the hinges c, at their adjacent and front edges, to the front edge of the partition-piece A. These sections are, in a manner similar ⁶⁵ to the sections R and R', closed, on three sides, by the outside panel-pieces C' and the inside pieces C''. The sections R and R' are open toward the front, and the sections F and F' have their open side turned toward the rear ⁷⁰ when the same are closed, as shown in Figs. 1 and 3, so that, when turned to the position shown in Figs. 2 and 4, their open side will be in the same direction as the open side of the sections R and R'. The front edges of ⁷⁵ the shelves a are preferably faced with narrow vertical strips k, to retain the spools of cotton in the compartments.

In the bottom of the cabinet, is formed a place for the drawer G, for which is provided ⁸⁰ inclined ways, or slides e. By this means, not only will the spools of cotton, which are placed therein on their sides in rows extending from the front to the back of the drawer between the partition-slats d, always tend to roll toward the front of the drawer, but the drawer, itself, will be easier to manipulate. It is evident that the spools always being in the front end of the drawer, it will not be necessary to pull the drawer out but a short distance to get ⁸⁵ at the spools. For this reason, I secure to the under side of the drawer a stop-strip h, and a cross-bar i to the framing of the case, against which the stop h abuts when the drawer is drawn out a short distance, preventing the ⁹⁰ further withdrawal of the drawer except when the front end of the drawer is raised, as shown

in Fig. 5, when the stop *h* will ride over the cross-bar *i*. When the stop *h* has passed the cross bar *i* the drawer can again be allowed to rest on its slides and be completely withdrawn. In order to permit the drawer to be raised, as described, to pass the stop *h* over the cross-bar *i*, the sides of the drawer and the partition slats *d* are cut down, so as to be narrower at the middle portions than at their ends or at the front and rear ends of the drawer.

In a cabinet such as described, one side, as *W*, is used for the spools of white thread, and the other, *B*, for the black, placing the different numbers in the several individual compartments of the sections *R* and *F* and *R'* and *F'*, while the drawer is used for the colored thread.

The main features of advantage are: the comparatively limited counter-space occupied by the cabinet, as a whole, *i. e.*, its compactness, combined with the ease with which the different sorts of either color—black or white—can be gotten at, and the fact that all sorts of the desired color are at once presented to view when one section, *F* or *F'*, is simply turned to the position shown in Figs. 2 and 4, and this, without inconvenience, when the cabinet is used in a clear space.

The features of advantage in the drawer are self-apparent—the spools always being at the front of the drawer, where they may be gotten at without pulling the drawer completely out, and the drawer being supported on inclined ways will be more easily pulled

out, the inclination of the ways not being so abrupt as to permit the drawer to open itself.

It is evident, from the foregoing description, that the general form of cabinet, illustrated herewith, might be considerably modified, to meet the requirements in particular cases, without materially departing from the essential features of my invention.

I claim—

1. In a thread cabinet, the combination with stationary receptacles, of a partition-piece extending beyond the same, and receptacles hinged to the outer edge of the partition-piece: substantially as and for the purposes described.

2. In a thread cabinet, the combination with a drawer and inclined slide-ways therefor, of a stop secured to the underside of the drawer, and a stationary cross-bar, the side parts of the drawer being reduced in the middle portion of the length: substantially as and for the purposes described.

3. In a thread cabinet, the combination with stationary sections and hinged receptacles, of a drawer mounted beneath the same provided with inclined slide-ways: substantially as and for the purposes described.

In testimony whereof I hereunto affix my signature, in presence of two witnesses, this 16th day of August, 1892.

FREDERICK A. GOODRIDGE.

Witnesses:

A. RAMEL,
F. R. CORNWALL.
